SURFACE CONSTRUCTION FOR CEILINGS, WALLS, AND THE LIKE

Filed Oct. 21, 1939

UNITED STATES PATENT OFFICE

2,218,378

SURFACE CONSTRUCTION FOR CEILINGS,
WALLS, AND THE LIKE

Frank G. Dresser, Providence, R. I.

Application October 21, 1939, Serial No. 300,507

4 Claims. (Cl. 72—23)

This invention relates to improvements in surface constructions for ceilings, walls and the like. More especially it provides improvements in surface constructions of the general type disclosed in my co-pending application for patent Serial No. 274,893, filed May 22, 1939, but which are particularly applicable to regions, such as ceilings of buildings, where plaster or the like may not be a constituent part of the structure.

10 The invention is herein disclosed as embodied in the construction of a ceiling and the walls of a building, but it will be obvious that the structural features hereinafter disclosed have general application where an inexpensive, permanent and attractive composite-block surface is desired.

It is among the objects of the invention to provide plate-like construction units having hard, durable and attractive faces, and whose rear sides are of material which has a strong affinity for 20 adhesives, whereby the units may be quickly and effectively associated together, in edge to edge relation, on a suitable support, and be securely and permanently held by an adhesive.

Another object is to provide a support for the 25 units having a surface of material which itself has a strong affinity for adhesives, to promote the said security and permanence of the associated units.

Other features relate to the composite structure of the units and to the manner of assembling their component parts, all of which will more particularly appear in connection with the following detailed description.

The mentioned objects and results may be attained by employing rectangular plate units of sheet stock, preferably sheet metal, of any suitable area, which may be arranged edge to edge in rows, or in staggered relation, across and along the ceiling or other region which is being treated. 35 The units preferably will be a composite of materials with a stiff metal body which may be faced with aluminum and backed by a material having a strong affinity for adhesives. The exposed aluminum face may be oxidized to provide an extremely hard surface with attractive color effects. The backing material preferably will be in block form for fitting within side flanges on the iron bodies, and may be securely held therein by any suitable mechanical fastening devices.

50 The support for the units conveniently may be sheet material such as fibre board which will be nailed or otherwise secured to the usual beams of a ceiling, or to the studding in walls. Preparatory to mounting the surface units, the surface of the fibre board, and the back sides of the units

will be coated with shellac or other suitable adhesive, after which the units may be mounted by merely pressing the coated back of each unit against the coated surface of the support. The adhesive will be sufficiently tacky to initially hold the units wherever they may be placed on the supporting fibre board, and, after setting, provides a strong and durable union between the backs of the units and the support. 5

The units may be formed, some with plane 10 faces and some with angular faces, the latter for fitting corners at the junctures of walls and of walls with ceiling.

It is intended that the patent shall cover, by suitable expression in the appended claims, whatever features of patentable novelty exist in the invention disclosed.

In the accompanying drawing:

Figure 1 is a perspective illustrating an upper corner of a room, at the juncture of walls with 20 ceiling, and showing a ceiling and wall structure embodying features of my invention;

Figure 2 is an elevation in section thru a fragment of the ceiling of Figure 1;

Figure 3 is a perspective of the facing element 25 of one of my surface units;

Figure 4 is a perspective of the body or lining element which fits within the facing element of Figure 3;

Figure 5 is a perspective of a block of backing 30 material which fits within the lining element of Figure 4;

Figure 6 is a sectional view, on a larger scale, thru a completed surface unit, and showing the securing means for holding the backing material within the lining; and

Figures 7 and 8 show units suitable for use at corner locations.

Referring to the drawing, the beams 6, and the studding 8 may be regarded as representative of the frame structures customarily found respectively at ceiling and at wall locations in buildings. They are utilized, according to my present invention, for mounting sheet material which in turn supports the multiplicity of surface 40 units 10, 12 hereinafter described in detail in connection with the detail illustrations in the drawing. The sheet material may be any suitably strong and porous stock having strong affinity for ordinary adhesives, but I prefer to employ one of the available materials commonly referred to as fibre board which, in suitably large sheets 14, may be nailed to the beams 6 in the ceiling region, and to the studding 8 in the wall 45 50 55

regions, if the ceiling and walls are to be similarly treated.

Each surface unit 10 comprises a facing element 16 in the form of a flanged rectangular plate, a rectangular body or lining element 18 similarly flanged and of size to nicely fit within the flange of the facing element, and a rectangular backing element 20 for fitting within the flange of the lining element.

10 The facing element 16 and the lining element 18 may be made of any suitably strong and durable material but I prefer to employ aluminum for the facing and iron for the lining. In Figure 3, such an aluminum facing element is represented as stamped out of sheet stock, with a plurality of tongues 22 formed at each edge of flange, some of which at each side are to be turned inward as retainers for the lining 18, and some of which on two adjacent sides are to be 20 turned outward to serve as spacers between units.

The lining element 18 similarly may be stamped out of sheet stock and, as seen in Figure 4, a plurality of retaining tongues 24 are provided on the plate body of the lining, projecting rearward in parallelism with the flanges, these tongues being adapted to extend thru the backing element 20 and to be bent over against the back surface of that element to retain the backing within the lining element.

30 Figure 5 represents a backing element 20 in block form which conveniently may be stamped or cut from any suitable strong and adequately porous sheet stock. Preferably it will be of fibrous composition material, such as one of the 35 available products generally referred to as fibre board. Each block 20 is formed with a plurality of holes 26 for receiving the tongues 24 of the lining, and a depression 28 adjacent to each hole, at the back surface of the block, constitutes 40 a seat into which the turned over portion of a tongue 24 may seat so as to rest below the plane of the back surface of the block. As represented, the bottoms of depressions 28 have slight inclination from their respective holes 26 toward the 45 plane of the back surface of the block.

Assembling of the surface units 10 involves only the inserting of a lining 18 within a facing element 16, and the bending inward of some of the tongues 22 on each side for retaining the 50 lining, and the bending outward of others of the tongues 22 on two adjacent sides, to serve as as spacers between units. Then a backing block 20 is inserted within the lining with the tongues 24 extending thru the holes 26, to be bent against 55 the block, into the depressions 28 at the back of the block. The unit is now ready for mounting on a fibre board support 14.

Assuming that a multiplicity of the surface units 10 are ready for mounting, shellac or any

other suitable adhesive is smeared over the surface of the fibre board support 14, and over the fibrous backs of the surface units. Then the units may be stuck to the support in edge to edge arrangement, to provide a hard, attractive and durable surface for ceiling or wall, or other object, as the case may be.

Angular shaped surface units 12 may be provided for corner locations, as represented in Figure 7, and as shown embodied in the construction 10 of Figure 1. In this case the lining and the fibrous backing preferably will be each in two parts.

In Figure 8 another angular form of surface unit is represented, suitable for projecting corners.

It will be obvious that my invention provides an effective and economical surfacing for ceilings, walls and the like without need for plaster to hold the surface units.

20

I claim:

1. A surface construction unit for ceilings and the like, comprising a lining element of strong and stiff metal and, fitting over said lining, a flanged facing element of relatively thin metal 25 adapted to provide a hard and attractive surface, and having tongues on its flange for retaining the said lining within its flanges, combined with a body of fibrous material secured on the back of the lining whereby said unit may be bound 30 by adhesion to a support.

2. A surface construction unit for ceilings and the like, comprising a rectangular lining element of strong and stiff metal and, fitting over said element, a flanged facing element of relatively 35 thin metal adapted to provide a hard and attractive surface and having means for holding the lining within its flanges; retaining elements projecting rearward from said lining; and a block of fibrous material backing said lining element; there being holes thru said block and said retaining elements of the lining extending thru the holes and having their end portions bent into retaining engagement with the block.

3. A surface construction unit as in claim 2, 45 wherein there is a depression in the back surface of the block adjacent to each said hole, and said bent portions of the retaining elements being seated in said depressions.

4. A surface construction unit for ceilings and the like, comprising a flanged facing element of relatively thin light metal adapted to provide a hard and attractive surface, a lining element of strong and stiff metal fitting within said facing element, an element of fibrous material backing 55 said lining element, and means binding said elements together to form said unit.
